(57) **CLAIM**

The ornamental design for a charging station as shown and described.

DESCRIPTION

FIG. 1 is a perspective view of top and left side of a charging station showing our new design;

FIG. 2 is a perspective view of bottom and right side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front view thereof, showing the charging station in a state of use;

FIG. 10 is a side view thereof, showing the charging station in a state of use; and,

FIG. 11 is a front view thereof, showing the charging station in a state of use.

The broken lines depict portions of the charging station that form no part of the claimed design.

1 Claim, 11 Drawing Sheets
